UNITED STATES PATENT OFFICE.

WILLIAM T. FINK, OF CARLYLE, ILLINOIS, ASSIGNOR OF ONE-HALF TO WILLIAM JOHNSTON, OF CARLYLE, ILLINOIS.

EXTENSIBLE TABLE.

1,158,125.

Specification of Letters Patent. Patented Oct. 26, 1915.

Application filed February 25, 1915. Serial No. 10,393.

To all whom it may concern:

Be it known that I, WILLIAM T. FINK, a citizen of the United States, residing at the city of Carlyle, in the county of Clinton 5 and State of Illinois, have invented certain new and useful Improvements in Extensible Tables, of which the following is a specification.

This invention relates to extensible tables 10 and has for its object to provide a table that may be extended beyond its permanent area by means of a plurality of removable extension plates surrounding the normal outer edge of the table and supported on 15 slidable supports which are normally adapted to be concealed from view between guide-members beneath the permanent table-top.

Another object is to provide a table that, when extended by means of said extension 20 plates, may have the shape of the permanent table-top or may be extended in a shape other than that of the permanent top by surrounding the edge of the permanent table-top by appropriately shaped extension 25 plates of this invention.

Another object of the present invention is to provide an extensible table of the character described, which is simple in operation, of cheap and strong construction, and 30 easy of operation.

An advantage of providing extension plates adapted to surround the outer edge of the permanent table-top is that, when enlarging the table-surface of a table embodying the present invention, it is not necessary to divide and move the pedestal as is the case with circular extension tables 35 of the ordinary construction, and, moreover, a table embodying the present invention, when extended, presents a better appearance than that of the ordinary extensible table.

Other objects and advantages of this invention are mentioned in this specification, and, furthermore, this invention consists in the novel features of construction and the combination and arrangement of parts set forth in the specification and pointed out in 45 the claims.

In the accompanying drawings, forming part of this specification, wherein like numbers of reference denote like parts wherever they occur, Figure 1 is a plan view looking 50 down upon the top of a table embodying the present invention with the extension

plates in place, a portion of one of said plates being broken away to show means for joining an extension plate to the permanent table-top, to the slidable supports, and to an adjoining extension plate; Fig. 1^a is 60 a perspective view, on a reduced scale, looking downwardly upon one of the extension plates of Fig. 1, removed from place adjacent the permanent table-top; Fig. 2 is a vertical elevation of the table shown in plan 65 view in Fig. 1; Fig. 2^a is a perspective view looking at an end of the extension plate shown in Fig. 1^a; Fig. 3 is a plan view looking up at the under side of a table of this invention with the extension plates in 70 place, the pedestal having been cut off transversely near the table-top; Fig. 4 is a cross sectional view on the line 4—4, Fig. 1; Fig. 5 is a cross sectional view of a fragment of the permanent table-top and associated parts on the line 5—5, Fig. 1; Fig. 6 is a cross sectional view of a fragment of 75 two adjoining extension plates and associated parts on the line 6—6, Fig. 1; Fig. 7 is a plan view on a reduced scale showing a 80 table embodying the present invention provided with a modified form of extension plates; and Fig. 8 is a detailed fragmentary view showing the relation of adjacent edges of the extension plates, the edge of the 85 permanent table-top, and the cam-shaped locking device prior to drawing, by means of said locking device, the extension plates toward each other and toward the edge of the permanent table-top to lock all parts in 90 place.

Although the drawings depict a table with a circular permanent top, it is, of course, understood that the permanent top of a table embodying this invention may be 95 of any other desired shape, such, for instance, as elliptical, oval, or polygonous with any desired number of sides, but for the purpose of illustration the table 1 embodying the present invention shown in the accompanying drawings and described in detail in this specification is one having a permanent top 2 of circular shape supported upon centrally located pedestal 3, there being an annular member 4 depending from the under side of said permanent top near the outer edge thereof and secured to said under side by any suitable means, and extending between said annular member and said pedestal, four similar pairs of guides 5 may be 105 110

provided, said guides being arranged in cross-shape as best seen in Fig. 3, each pair of guides being parallel to a radius of said annular member and to a radius of said permanent table-top, each pair of said guides being adapted slidably to support an extension-plate support 6, each of said extension-plate supports being slidable outwardly through an appropriate opening 7 in said 5 annular member adjacent an end of each pair of said guides and said extension-plate support, the width of said support being adapted to the space between two guide-members forming the pair supporting said extension-plate support slidable therein and the length of said extension-plate support being preferably adapted to the distance between the outer edge of said annular member at the mouth of said opening to said 10 pedestal, so that, when said slidable support for an extension-plate is drawn toward said pedestal, the outer end will be flush with the outer edge of said annular member adjacent the outer mouth of said opening 7. 15 Borne at an appropriate location on the under side of each slidable support 6, a locking and limiting device 8 may be provided, said device being adapted to perform certain locking functions hereinafter more 20 particularly described and being adapted, also, to limit the outward movement of said slidable support, said member being preferably cam-shaped and being eccentrically pivoted upon pivot 9 and supported, so pivoted, on the under side of said slidable support 6 in any suitable manner, said member being adapted to limit the outward movement of said slidable support by coming in contact with the inner edge of said annular 25 member adjacent the inner mouth of said opening 7 when said slidable support has been advanced sufficiently far outwardly for the purposes of this invention as hereinafter described. 30 Appropriate grasping means 10, such, for instance, as the finger pieces or grips counter-sunk in the under side of said slidable supports 6 shown in the accompanying drawings, may be provided as convenient 35 means for drawing said slidable supports forward and backward between the guide members, and at an appropriate location near the outer end of each slidable support 6, dowel-pin holes 11, preferably a pair of 40 said holes for each slidable support, may be provided. 45 Reinforcing members 12, such, for instance, as the reinforcing members 12 best seen in Fig. 3 disposed in cruciform upon 50 and secured to the under side of permanent table-top 2, may be provided for strengthening 55 said top and parts associated therewith.

Normally the size of the table embodying the present invention is that of the permanent table-top, but for increasing the size of

the table, extension-plates 13 are provided, said extension-plates being adapted to rest upon the portion of slidable supports 6 drawn outwardly beyond the outer edge of said permanent top in the manner hereinafter more particularly described. Said extension plates may be four in number, as best seen in Figs. 1 and 3, similar in size and shape and adapted to fit around the edge of permanent table-top 2 to form, when so surrounding said edge, a circular table of greater top-area than that of permanent table-top 2, an end of each extension-plate being adapted to meet an end of the next adjacent plate, and said ends may be more 70 intimately joined together by means of groove and tongue joints 14, 15, and by means of dowel-joints 16, 17, borne at appropriate locations by said ends of said extension plates. A dowel-pin 18 may be provided borne by the under side of each extension-plate near each end thereof, each of said dowel-pins being adapted to enter a corresponding one of said pair of dowel-pin holes 11 in slidable support 6 and being adapted 75 to hold said plate in place on said support, said dowels engaging said holes being adapted, also, to limit the inward movement of said slidable supports when said extension-plates are in place upon said supports, thus 80 with the aid of locking device 8 permitting said plates to be locked together and to permanent table-top 2, as hereinafter described. 85 The edge of permanent table-top 2 and the inner edge of each extension-plate 13 90 adjacent thereto may be joined together more intimately, when said plates are in place, by means of tongue 19 and groove 20, and by means of dowel-joints 21, 22, borne, 95 respectively, by said edges. 100 Normally, the permanent table-top 2 forms the table-top of the table of this invention, slidable supports 6 being pushed inwardly in their respective pair of guides 105 5 toward pedestal-column 3 so that the outer ends of said slidable supports are flush with the outer edge of annular member 4 adjacent the outer mouth of a corresponding opening 7, and so that said slidable supports are entirely withdrawn beneath said 110 permanent table-top 2. When it is desired to extend the table-top to form a table of greater area than that of said permanent table-top 2, slidable supports 6 are drawn 115 outwardly in their respective guides 5 as 120 far as limiting and locking device 8 will permit, said device being set in the position shown in Fig. 8, which position is one adapted to permit the protruding dowel-pin hole-bearing ends of each slidable support to be 125 protruded sufficiently far to allow a slight space between the edge of said permanent table-top 2 and the inner edges adjacent thereto of said removable extension-plates 13, and to permit a slight space between the 130

adjacent edges of adjoining extension-plates when said extension-plates are placed upon said protruding ends of said slideable supports with each dowel 18 inserted into a corresponding one of holes 11, as shown by the dot and dash lines in Fig. 1, said spaces being sufficiently great to permit said extension-plates to be placed about said outer edge of said table-top 2 on said supports with said dowel-pins in said openings, whereupon, said plates having been so placed, as shown by said dot and dash lines in Fig. 1, locking and limiting devices 8 are swung on their respective pivots, Fig. 8, to the position shown in Fig. 3, whereby, said pivots being eccentrically located in said device, said movement of said devices, permitting their cam-shaped portions to engage the inner edge of adjacent portions of annular member 4, will draw the inner edges of said extension-plates toward the edge of said permanent table-top 2, and will, also, draw the adjacent edges of adjoining plates together closing the spaces above-mentioned and drawing groove 20 upon tongue 19, grooves 14 upon tongue 15, causing the dowels 16 and 22 to enter corresponding holes 17 and 21, thus forming an intimate union of parts between said edge of permanent table-top 2 and the said inner edges of said plates 13 and between adjacent edges of said adjoining plates, and, said locking and limiting devices being jammed against the adjacent surface of portions of the inner edge of said annular member 4, all parts will be locked in the position shown by the full lines in Fig. 1, and, also, shown in Figs. 3, 4, and 6.

Fig. 7 shows a modified form of an extensible table embodying the present invention extended to increase the area provided by permanent table-top 2, in which modified form two opposite extension plates 13 have the greater portion of their outer circular edge and the surfaces adjacent thereto removed by cutting same away along similar cords of the arc of said outer circular edge, so that when all the extension plates 13 are in place surrounding the edge of permanent table-top 2, the shape of the extended table-top will approximate an elliptical form with said two opposite mutilated plates having their outer edges parallel to each other, as shown in said Fig. 7. This modified form is adapted, for instance, for use in a room the dimensions of which will not conveniently accommodate an extensible table embodying this invention extended in circular shape.

It is, of course, understood that many modifications from the circular form of permanent table-top 2, shown in the drawings, may be made in a table embodying the present invention, and that corresponding changes may be made in the shape of exten-

sion plates 13 to maintain in the extended table the form, whether circular, elliptical, oval, polygonous, or any other shape, the shape of said permanent table-top; or by constructing extension plates 13 with outer edges having an outline when in place different from that of the edge of said permanent table-top, a table may be provided extensible into any desired shape determined by the outline of said outer edges of said extension plates. Moreover, it is, of course, also understood, that the number of said extension plates may be greater or less than four, and that the number of slideable supports 6 with their associated parts may, also, vary from that shown in the accompanying drawings. Further, many other changes in the details of construction and arrangement of parts may be made without departing from the nature and spirit of the present invention.

I claim:

1. An extension table having a permanent top, a plurality of removable extension leaves constructed to fit about the edge of said top, slideable supports mounted to move radially with relation to the permanent top, interengaging means carried by each of said slideable supports and the abutting ends of each pair of said leaves, and manually-operable means for imparting a drawing action to the slideable supports with relation to the permanent top for drawing said supports inwardly and binding said leaves against each other and against the periphery of the permanent top.

2. An extension table having a permanent top, a plurality of removable extension leaves constructed to fit about the edges of said top, slideable supports mounted for radial movement with relation to the permanent top and arranged to be drawn outwardly beyond said permanent top, a downwardly-extending member carried by said permanent top and through which said slideable supports extend, cams mounted upon said slideable supports and acting upon said downwardly-extending member for imparting inward movement to said slideable supports when said cams are manipulated, and interengaging means between each of said supports and each of the leaves supported thereby constructed to cause said leaves to move inwardly with said slideable supports under the action of said cams.

3. An extension table comprising a permanent top, a plurality of leaves shaped to fit therearound, a plurality of radially-moving slideable supports carried by said permanent top, downwardly-extending dowel-pins carried by each of said leaves adjacent the ends thereof, each of said slideable supports being provided with elongated openings constructed to receive the dowel-pins of an abutting pair of said leaves, whereby inward move-

ment of the slidable supports will draw said leaves toward the permanent top and toward each other.

4. An extension table comprising a permanent top, a plurality of leaves shaped to fit therearound, a plurality of radially-moving slidable supports carried by said permanent top, downwardly-extending dowel-pins carried by each of said leaves adjacent the ends 10 thereof, each of said slidable supports being provided with openings constructed to receive the dowel-pins of an abutting pair of said leaves, and manually-operable means

carried by said slidable supports for imparting movement to said slidable supports inwardly of the permanent top and constructed to lock said slidable supports against outward movement after they have been moved to a predetermined degree. 15

In testimony whereof I hereunto affix my 20 signature in the presence of two witnesses.

WILLIAM T. FINK.
